COMBINED CLOCK AND RADIO CABINET

John W. Mason, Glenview, Ill.

Application September 4, 1958, Serial No. 52,504

Term of patent 3½ years

(Cl. D56—4)

Fig. 1

Fig. 2

Fig. 3

Fig. 4

Fig. 1 is a front perspective view of a combined clock and radio cabinet, showing my new design;

Fig. 2 is an end elevational view thereof;

Fig. 3 is a rear elevational view thereof; and

Fig. 4 is a bottom plan view thereof.

The dominant features of my design reside in the portions shown by full lines.

I claim:

The ornamental design for a combined clock and radio cabinet, as shown and described.
